UNITED STATES PATENT OFFICE.

EDWARD R. KNOWLES, OF BROOKLYN, NEW YORK, ASSIGNOR TO THE MUTUAL ELECTRIC MANUFACTURING COMPANY, OF NEW YORK.

AUTOMATIC CUT-OUT FOR ELECTRIC LAMPS.

SPECIFICATION forming part of Letters Patent No. 403,941, dated May 28, 1889.

Application filed March 23, 1886. Renewed July 25, 1887. Serial No. 245,275. (No model.)

To all whom it may concern:

Be it known that I, EDWARD R. KNOWLES, a citizen of the United States, residing at Brooklyn, in the county of Kings and State 5 of New York, have invented certain new and useful Improvements in Automatic Cut-Outs for Electric Lamps, of which the following is a full, clear, and exact description.

This invention relates to a certain novel 10 automatic cut-out for electric lamps, the object being to provide means for automatically throwing a lamp out of circuit, when, by failure of its carbons to approach each other from any cause, the resistance of the arc is unduly increased. It is well known that when the 15 arc becomes too long its resistance is so great as to reduce the current and consequently the illuminating-power, thus affecting the brilliancy of every lamp in the circuit. By this 20 invention I seek to obviate this difficulty; and to this end my invention consists in the combination of a fixed electro-magnet of comparatively low resistance with a movable electro-magnet of comparatively high resistance, the 25 latter, when strongly excited, moving upward and completing the circuit through the coil of the fixed magnet, and in the details of the improvement, all as hereinafter particularly set forth and claimed.

30 In the accompanying drawing, which is a side elevation of a lamp having my invention applied thereto, A designates the box or frame inclosing the machinery of an arc lamp, whose main regulating-magnet is represented by B. The line-wire *a* passes through the regulating 35 mechanism, then through the upper and lower carbons, and thence, as shown by *b b*, leaves the lamp.

E designates the metal base-plate, which 40 may be secured to any convenient point of attachment. This base-plate E carries a fixed electro-magnet, C, of comparatively low resistance, and a pivoted electro-magnet, C', of comparatively high resistance, both having iron 45 cores. The core of the magnet C' is in metallic communication at its base or pivot *c* with the base-plate E, and on this pivot the magnet C' swings up and down, its upward position being indicated by dotted lines, and the 50 extent of its fall or downward movement by full lines, and said downward movement be-

ing regulated by adjustment of a set-screw, *d*. At the point *x* two branch wires are in communication with the main wire *a*. One of these wires *e* passes around the iron core of 55 the magnet C', so as to form its exciting-bobbin, and, emerging, joins the line-wire *b* at *y*. This bobbin is of high resistance. The other wire, *f*, runs from *x* to the frame E, with which it is connected electrically at any convenient 60 point, as at *z*. The magnet C is wound with a coil of wire, *g*, of lower resistance than the magnet C'. One end of this coil passes through an aperture in the core at *v*, being insulated from the metal of said core, and the other end 65 of the coil connects, as shown, with the line-wire at *y*. By this arrangement the wire of the magnet C', connected at *x* and *y*, forms a loop or shunt of high resistance across the arc, and in the ordinary operation of the lamp a 70 slight current passes through this wire, but not enough to cause any movement in the pivoted magnet. The relation of parts in this state is shown by full lines in the drawing.

If the distance between the carbon points 75 is increased from any cause to too great an extent, the resistance of the arc is greatly augmented, and this throws more current into the shunt-wire *e*, that constitutes the exciting-wire of the magnet C'. As the magnetism of 80 the core of said magnet increases, it swings on its pivot under the influence of its attraction toward the core of the magnet C, and, swinging upward, it strikes against the protruding end of the core-wire at *v*, coming into electrical connection therewith. This completes 85 the circuit from *x* by *f* to the frame E, thence through the frame and core of the magnet C' to the end of the wire *g* at *v*, and thence through the coil of the magnet C to *y* and the line-wire *b*. It will thus be seen that when this connection is made the magnet C instantly becomes strongly excited and holds the magnet C' up, maintaining the connection, and giving passage for the current. The magnet 95 C', as a high-resistance shunt, again becomes comparatively passive, but is still retained in its upward position by the magnet C.

What I claim as my invention, and desire to secure by Letters Patent, is—

1. In an automatic cut-out for a line-circuit, the combination of a fixed electro-mag-

net wound with a coil of comparatively low resistance connected to the line-wire in a normally-open shunt, and a vibrating electro-magnet of comparatively high resistance having an exciting-bobbin connected to the line-wire in a normally-closed shunt, the vibrating magnet being pivoted in close proximity to the fixed magnet, whereby, when strongly excited, the vibrating magnet will contact with and complete the circuit through the fixed magnet, as and for the purpose set forth.

2. In an automatic cut-out for a line-circuit, the combination of a fixed electro-magnet wound with a coil of comparatively low resistance connected in a normally-open shunt at one end to the line-wire and having its other end free and projecting from the core but insulated therefrom, and a vibrating shunt electro-magnet having a bobbin of comparatively high resistance connected to the line-wire in a shunt around the lamp, said vibrating magnet being pivoted in close proximity to the fixed magnet, whereby, when the resistance of the arc is increased, the vibrating magnet will come in contact with the fixed magnet and complete the circuit through the same, as and for the purpose set forth.

3. The combination of the fixed electro-magnet C, having one end of its wire g connected to the outgoing line, and the other end insulated and protruding from the pole at v, and the frame E, connected to the incoming line, with the vibrating shunt electro-magnet C' located in proximity to the fixed magnet and

in electrical contact with the frame E, substantially as described.

4. A cut-out or protecting shunt for a line-circuit, comprising a fixed electro-magnet, C, wound with a coil of wire, g, of low resistance, one end of which passes through an aperture in the core at v and is insulated from the metal of said core, and the other end of which is connected with the line-wire at y, in combination with the vibrating magnet C', and the bobbin e, passing around the core of said magnet and connected to the line at x and y, forming a loop or shunt of high resistance, substantially as set forth, for the purpose specified.

5. In an automatic cut-out for a line-circuit, the combination of a fixed electro-magnet wound with a coil of comparatively low resistance connected at each end to the line-wire in a normally-open shunt, and a vibrating electro-magnet pivoted in close proximity to the fixed magnet and encircled by a bobbin of comparatively high resistance connected to the incoming and outgoing line-wire at its respective ends, constituting a loop or shunt of comparatively high resistance across the arc, substantially as described.

In testimony whereof I have hereunto set my hand this 9th day of February, A. D. 1886.

EDWARD R. KNOWLES.
